J. D. PEDERSEN.

FIREARM.

APPLICATION FILED DEC. 16, 1919.

1,355,424.

Patented Oct. 12, 1920.

Inventor:

John D. Pedersen,
By his Atty, Tiff Richards.

UNITED STATES PATENT OFFICE.

JOHN D. PEDERSEN, OF JACKSON, WYOMING.

FIREARM.

1,355,424.

Specification of Letters Patent. Patented Oct. 12, 1920.

Original application filed July 30, 1915, Serial No. 42,774. Divided and this application filed December 16, 1919. Serial No. 345,177.

To all whom it may concern:

Be it known that I, JOHN D. PEDERSEN, a citizen of the United States, residing in Jackson, in the county of Lincoln and State of Wyoming, have invented certain new and useful Improvements in Firearms, of which the following is a specification.

This invention relates more especially to that class of firearms which is usually designated as small-arms, and a principal object of the invention is to furnish an improved grip-safety device particularly applicable to auto-loading and automatic pistols.

15 One class of small-arms to which my present improvements are applicable, includes the auto-loading pistols having a grip-stock, or handle portion of the frame or receiver of the pistol, adapted to receive a 20 safety device which is operable by hand grip or compression.

An improved auto-loading pistol of this kind is described in my co-pending application (renewal) Serial No. 311689, filed 25 July 17, 1919, and the improvements herein described are also illustrated in my said prior application, but are not specifically claimed therein. Therefore for convenience of illustration, I have herein shown my 30 present improvements as arranged and applied to the particular kind of auto-loading pistol which is illustrated in the drawings of said application, to which reference may be had.

35 A feature of my invention is that it is a grip-safety device arranged to prevent discharge of the firearm by locking the sear member and the firing member or hammer in firing position, and also, where the firearm is provided with a sliding breech action comprising a firing-pin, by locking the sliding breech action to prevent contact between the firing-pin and cartridge, so that 40 action of the firing member or hammer will 45 not explode the cartridge.

Another feature of my invention is that it is provided with what I term a resisting and retracting member. One purpose of the resisting and retracting member is to move 50 downward or retract a slidable member or controller when the firing member or hammer is moved from firing position to fired position, which slidable member or controller is in upward, or locking position 55 when the firing member or hammer is in

firing position, and thus locks the sear member and firing member or hammer in firing position, and locks the sliding breech action of the firearm, when the firearm is provided with a sliding breechaction, the 60 slidable member or controller being held in such upward or locking position by the grip-safety portion of my invention. A second purpose of such resisting and retracting member is to engage said slidable member 65 or controller, when the slidable member or controller is in such upward or locking position, and at the same time to engage, when the firing member or hammer is in firing position, a means for connecting the firing 70 member or hammer to the main spring or firing spring, and thereby to resist or prevent movement of the firing member or hammer from firing position to fired position. 75

In the accompanying drawings, which illustrate an embodiment of my grip-safety device:—

Figure 1, is a side elevation, partly broken away to show the details of a pistol having 80 a sliding breechaction comprising a firing-pin, and provided with my grip-safety device, the grip-operable or grip-safety portion of my device being grip-compressed to unlock the slidable member or controller, 85 the firing member or hammer being unlocked from the sear member by trigger action and moved to fired position, the slid- 90 able member or controller being in unlock- 95 ing position, and the resisting and retracting member being in position whereby it has re- 100 tracted or moved the slidable member or controller to unlocking position, or down- 105 ward.

Fig. 2, is a fragmentary side view on 95 larger scale than Fig. 1, partly broken away to show the details, of the rear portion of 100 a pistol provided with my grip-safety device, the sliding breechaction being removed, the grip-operable or grip-safety member be- 105 ing grip-compressed to unlock the slid- 110 able member or controller, the slidable member or controller being in unlocking position, the firing member or hammer being moved to firing position prior to being locked in such position by the sear member, the re- 115 sisting and retracting member being in re- 120 sisting and retracting position, and the trigger member being in retracted or rear position in contact with the sear member 125

prior to movement of the trigger member to forward position.

Fig. 3, is a fragmentary side view, on substantially the same scale as Fig. 2, partly broken away to show the details, of a pistol provided with my grip-safety device, the sliding breechaction being removed, the grip-operable or grip-safety member not being grip-compressed and in position of safety, and thereby blocking the slidable member or controller in locking position, the firing member or hammer being locked in firing position by the sear member, the resisting and retracting member being in position which has permitted movement of the slidable member or controller to locking position, and is in readiness to act as a resisting member for the firing member or hammer to retain it in firing position, and the trigger member being in forward position.

Fig. 3^a is a sectional detail plan view, of the resisting and retracting member of my grip-safety device, on the line 3^a—3^a of Fig. 2.

Fig. 3^b is a detail plan view, on an enlarged scale of the top portion of my grip-safety device as shown in Fig. 3.

Fig. 3^c is a detail sectional view, on an enlarged scale, on the line 3^c—3^c of Fig. 3, looking in the direction of the arrow.

Fig. 4, is a detail sectional view on the line 4—4 of Fig. 3, looking in the direction of the lower arrow and on an enlarged scale, the grip-operable or grip-safety member being removed.

Fig. 5, is a detail sectional view, on an enlarged scale, on the line 4—4 of Fig. 3, looking in the direction of the upper arrow, part of the front of the rear portion of the pistol being removed.

Similar reference characters or numerals refer to similar parts throughout the several views.

45 My grip-safety device comprises with the various parts of my device to be hereinafter described, a firing member or hammer H.

The firing member or hammer H is pivotally supported on the grip-stock of the pistol and is movable to firing position, and to fired position, the grip-stock of the pistol being bored out or otherwise suitably cut away to receive the firing member or hammer and the various other parts of my device.

55 The firing member or hammer H is provided with a firing-notch or cock-notch 8^j.

The sear member S is pivotally supported on the grip-stock of the pistol and is provided with a locking-face 17^b which is engageable with the cock-notch 8^j of the firing member or hammer H, and is provided with an end-face 17^d which is engageable with the trigger member F.

The slidable member or controller N is movable to locking position and to unlock-

ing position, being, as shown, movable upwardly and downwardly, and is guided at its upper end by guide-faces 10 and 11. The slidable member or controller is provided at its upper end with an end 14^a which is engageable with the sliding breech action. A slot 12 is provided in the slidable member or controller N to receive the end of the trigger member F and allow a slight movement or play of the trigger member therein. The slidable member or controller N has near its lower end a shoulder 14^p which has an upper engaging surface or face 14^e, on either side of the slidable member or controller. The slidable member or controller N is provided, adjacent to and below the slot 12, with end-faces or bottom-faces 14^c. A spring actuated contractor 13 carried by the slidable member or controller N, contacts or engages the face 17^b of the sear member S to move the sear member inwardly, and thereby move the end-face 17^d of the sear member forwardly for engagement therewith of the trigger member F. The slidable member or controller N is provided at its lower end with an actuator 14^m. The actuator 14^m comprises a stem or spindle 14 and a spring 15. The stem or spindle 14, is rigidly attached at its upper end to, or may be integral with, the slidable member or controller. The stem or spindle 14 is seated in or extends through a member or boss 16 mounted on the grip-stock of the pistol, and thus, in addition to its function as a stem or spindle for the spring 15, provides by its engagement with the member or boss 16 a means for preventing inward shifting of the slidable member or controller N at its lower end. But I do not restrict myself to this means to prevent shifting, as any means suitable to prevent shifting of the lower end of the slidable member or controller may be employed.

The spring 15 surrounds the stem or spindle 14, being seated on the upper side or face of the member or boss 16 and abutting at its upper end the lower side or face of the shoulder 14^p of the slidable member or controller N, the tendency of the spring 15 being to move or force the slidable member or controller upwardly.

The grip-operable or grip-safety member G is pivotally attached at its lower end to the grip-stock of the pistol by a pivot pin g, preferably in the manner described and set forth in my co-pending application (renewal) Serial No. 311,689, filed July 17, 1919. The grip-operable member G closes the space 2^s in the grip-stock and is yieldable or hand compressible, the grip-operable or grip-safety member being, when in position of safety engageable at its upper end G' with the frame of the pistol and releasable from this engagement by grip-compression. The grip-operable or grip-safety

member G is provided with locking-prongs 7^a, which are engageable, when the grip-operable or grip-safety member is in position of safety, with the end-faces or bottom faces 5 14^c of the slidable member or controller N, to block or retain the slidable member or controller in upward locking position, the grip-operable or grip-safety member being releasable from this engagement by grip- 10 compression.

The main spring or firing spring 8^a is seated at its lower end in the grip-operable or grip-safety member G, preferably in the manner described and set forth in my said 15 co-pending application Serial No. 311,689, filed July 17, 1919. The spring 8^a surrounds the stem or spindle of the cupped plunger 8^c, which plunger moves or slides between the grip-operable or grip-safety member G 20 and a guide-face 17, formed in the grip-operable or grip-safety member, the plunger 8^c thus engaging the grip-operable or grip-safety member G, the pressure of the spring 8^a being upward and the purpose of the 25 spring 8^a being to move the firing member or hammer H to fired position, and to afford grip-compression of the grip-operable or grip-safety member, and to return the end 30 G' of the grip-operable or grip-safety member to engagement with the frame of the pistol after grip-compression. The rod 8^b is pivotally attached at its upper end to the firing member or hammer H, and at its lower end is seated in the cupped portion of the 35 plunger 8^c, the lower end of the rod being rounded or otherwise suitably arranged to afford a ball and socket connection or movement between the rod and the cupped portion of the plunger. The rod 8^b is provided 40 with a shoulder 16^a, which affords upper faces 18, and 18', on the sides of the rod.

The resisting and retracting member S' is pivotally supported on the grip-stock and comprises two rocker-arms, Figs. 3^a and 5, 45 having forward end-faces S¹⁰ and rearward end-faces S¹², the forward end-faces S¹⁰ engaging the upper faces 14^e of the shoulder 14^p of the slidable member or controller N, and the rearward end-faces S¹² engaging the 50 faces 18 and 18' of the rod 8^b.

The trigger member F is movable forwardly by means not shown, and by pull thereon is movable rearwardly, and is received in the slot 12 of the slidable member 55 or controller N as before stated, and has an end 6^a for engaging the end face 17^a of the sear member S, and a recess 6^m for said end face.

In operation: The firing member or hammer H being in fired position, Fig. 1, is moved to firing position, or cocked, Figs. 2 and 3, by suitable cocking means, or, by contact therewith of a roller R, due to rearward movement of the sliding breech action 65 where the pistol is provided with such

breech action, and is locked in firing position by the sear member S, which is actuated or pressed rearwardly by the contactor 13. Grip-compression of the grip-operable or grip-safety member G being released 70 returns the end G' thereof to engagement with the grip-stock, and the slidable member or controller having been moved upward by pressure of the actuator 14^m, the slidable member or controller N is blocked or locked 75 in upward position by engagement of the locking-prongs 7^a with the end-faces or bottom faces 14^c of the slidable member or controller N, which locks the sear member S and firing member or hammer H in firing 80 position, and, when the pistol is provided with a sliding breechaction, also locks such breechaction against rearward movement. The rearward end-faces S¹² of the resisting and retracting member S' engaging the 85 faces 18 and 18' of the rod 8^b prevent or resist movement of the firing member or hammer H to fired position because of the engagement of the forward end faces S¹⁰ of the resisting and retracting member with the 90 faces 14^e of the slidable member or controller N, the slidable member or controller being blocked against movement as above stated by the grip-operable or grip-safety member G. 95

The firing member or hammer H being in firing position, Fig. 3, grip-compression of the grip-operable or grip-safety member G releases the slidable member or controller for movement to downward or unlocking 100 position. Pull upon the trigger member F moves the sear member S to release the firing member or hammer H for movement to fired position. The firing member or hammer H when actuated by the spring 8^a moves the 105 rod 8^b upwardly, which rod carries with it the rearward end S¹² of the resisting and retracting member S', and the forward ends S¹⁰ of the resisting and retracting member S' being in contact with the upper surfaces 110 14^e of the shoulder 14^p of the slidable member or controller N, move or draw the slid- 115 able member or controller N downwardly against the compression of the actuator 14^m, and into unlocking position.

Having thus described my invention, I claim:

1. In a firearm in combination, a frame of said firearm, a firing member movable to firing position and to fired position, sear means engageable with said firing member, slidable means, means for moving said slid- 120 able means in direction to lock said sear means and firing member in firing position, a grip-operable member engageable with 125 said frame and engageable with said slid- able means to block the slidable means in said locking position, and releasable from both said engagements by grip-compression, spring means, means for connecting said fir- 130

ing member to said spring means for moving the firing member to fired position, and affording grip-compression of the grip-operable member, and for returning the grip-operable member to engagement with said frame after grip-compression, means for engaging said connecting means and for engaging said slidable means to resist movement of said firing member from firing position to fired position, and to move said slidable means in direction reverse to the first mentioned direction when said firing member is moved to fired position, and trigger means engageable with said sear means for moving the sear means to release said firing member for movement from firing position to fired position.

2. In a firearm, in combination, a sliding breechaction, a frame of said firearm, a firing member movable to firing position and to fired position, slidable means engageable with said sliding breechaction, means for moving said slidable means in direction to lock said sliding breechaction, and lock said sear means and firing member in firing position, a grip operable member engageable with said frame and engageable with said slidable means to lock the slidable means in said locking position, and releasable from both said engagements by grip-compression, spring means, means for connecting said firing member to said spring means to move the firing member to fired position, and affording grip-compression of the grip-operable member, and for returning the grip-operable member to engagement with said frame after grip compression, means for engaging said connecting means and for engaging said slidable means to resist movement of said firing member from firing position to fired position, and to move said slidable means in direction reverse to the first mentioned direction when said firing member is moved to fired position, and trigger means engageable with said sear means for moving the sear means to release said firing member for movement from firing position to fired position.

3. In a firearm, in combination, a frame of said firearm, a firing member movable to firing position and to fired position, sear means engageable with said firing member, slidable means, means for moving said slidable means in a direction to lock said sear means and firing member in firing position, means for guiding said slidable means in its sliding movement, means for preventing shifting of said slidable means, contacting means between said slidable means and said sear means, a grip-operable member engageable with said frame and engageable with said slidable means to block the same in said locking position, and releasable from both said engagements by grip-compression, spring means, means for connecting said

firing member to said spring means to move the firing member to fired position, and affording grip-compression of the grip-operable member, and for returning the grip-operable member to engagement with said frame after grip-compression, means for engaging said connecting means and for engaging said slidable means to resist movement of said firing member from firing position to fired position, and to move said slidable means in direction reverse to the first-mentioned direction when said firing member is moved to fired position, and trigger means engageable with said sear means for moving the sear means to release said firing member for movement from firing position to fired position.

4. In a firearm, in combination, a sliding breechaction, a frame of said firearm, a firing member movable to firing position and to fired position, sear means engageable with said firing member, slidable means engageable with said sliding breechaction, means for moving said slidable means in a direction to lock said sliding breech action, and lock said sear means and firing member in firing position, means for guiding said slidable means in its sliding movement, means for preventing shifting of said slidable means, contacting means between said slidable means and said sear means, a grip-operable member engageable with said frame and engageable with said slidable means to block said slidable means in said locking position, and releasable from both said engagements by grip-compression, spring means, means for connecting said firing member to said spring means to move the firing member to fired position, and affording grip-compression of the grip-operable member, and for returning the grip-operable member to engagement with said frame after grip-compression, means for engaging said connecting means and for engaging said slidable means to resist movement of said firing member from firing position to fired position, and to move said slidable means in direction reverse to the first-mentioned direction when said firing member is moved to fired position, and trigger means engageable with said sear means for moving the sear means to release said firing member for movement from firing position to fired position.

5. In a firearm, in combination, a frame of said firearm, a firing member movable to firing position and to fired position, a sear member engageable with said firing member, a slidable controller, means for moving said slidable controller upwardly to lock said sear member and firing member in firing position, means for guiding said slidable controller in its sliding movement, means for preventing shifting of said slidable controller, a contacting member between said

slidable controller and said sear member, a grip-safety member engageable with said frame and engageable with said slidable controller to block the slidable controller in upward position, and releasable from both said engagements by grip-compression, a spring, means for connecting said firing member to said spring for moving said firing member to fired position, and affording grip-compression of the grip-operable member, and for returning the grip-operable member to engagement with said frame after grip-compression, a resisting and retracting member for engaging said connecting means and for engaging said slidable controller, and a trigger member engageable with said sear member.

6. In a firearm, in combination, a sliding breechaction of said firearm, a frame of said fire-arm, a firing member movable to firing position and to fired position, a sear member engageable with said firing member, a slid- 20 able controller engageable with said sliding breechaction, means for moving said slid- 25 able controller upwardly to lock said sliding breechaction, and lock said sear member and firing member in firing position, means for guiding said slidable controller in its sliding movement, means for preventing shifting of 30 said slidable controller, a contacting member between said slidable controller and said sear member, a grip-safety member engageable with said frame and engageable with said slidable controller to block the slidable controller in upward position, and releasable 35 from both said engagements by grip-com- 40 pression, a spring, means for connecting said firing member to said spring for moving said firing member to fired position, and afford- 45 ing grip-compression of the grip-operable member, and for returning the grip-operable member to engagement with said frame after grip-compression, a resisting and retracting member for engaging said connecting means and for engaging said slidable controller, 50 and a trigger member engageable with said sear member.

7. In a firearm, in combination, a frame of said firearm, a firing hammer movable to 55 firing position and to fired position and pro- 60 vided with a cock-notch, a sear member pro- 65 vided with an upper end face for engaging said cock-notch, and provided with a lower end-face, a slidable controller an actuator 70 for moving said slidable controller upwardly to lock said sear member and firing member in firing position, means for guiding said 75 slidable controller in its sliding movement, means for preventing shifting of said slid- 80 able controller, a spring actuated contacting member carried by said slidable controller and engaging said sear member, a grip- 85 safety member pivotally attached at one end thereof to said grip-stock and engageable at the other end thereof with said frame and 90 engageable with said slidable controller to block said slidable controller in upward position, and releasable from both said en- 95 gagements by grip-compression, a rod pivot- 100 ally attached at the upper end to said firing member, a spring seatably connected to said grip-safety member, movable means engag- 105 ing said grip-safety member for providing an abutment for the upper end of said spring and a seat for the lower end of said rod, a 110 resisting and retracting member for engag- 115 ing said rod and for engaging said slidable controller, and a trigger member engageable with said lower end-face of the sear member.

8. In a firearm, in combination, a frame 115 of said firearm, a firing hammer movable to firing position and to fired position and pro- 120 vided with a cock-notch, a sear member pro- 125 vided with an upper end-face for engaging said cock-notch and provided with a lower end-face, a slidable controller provided with a slot for receiving a trigger member, and provided with bottom faces, and provided with a shoulder having upper surfaces and an under face and an extending stem from 130 said under face, guide-faces for the slidable controller at its upper end, a boss mounted on said grip-stock for providing a seat for said stem and for preventing shifting of said slidable controller at its lower end, a 135

engageable with said slidable controller to block said slidable controller in upward position, and releasable from both said engage- 70 ments by grip-compression, a rod pivotally attached at the upper end to said firing mem- 75 ber, a spring seatably connected to said grip- safety member, movable means engaging said grip-safety member for providing an abutment for the upper end of said spring and a seat for the lower end of said rod, a 80 resisting and retracting member for engag- 85 ing said rod and for engaging said slidable controller, and a trigger member engageable with said lower end-face of the sear member.

9. In a firearm, in combination, a sliding breechaction, a frame of said fire-arm comprising a grip-stock, a firing member mov- 20 able to firing position and to fired position, and provided with a cock-notch, a sear mem- 25 ber provided with an upper end-face for 85 engaging said cock-notch and provided with a lower end face, a slidable controller en- 90 gageable with said sliding breechaction, an actuator for moving said slidable controller upwardly to lock said sliding breechaction, 95 and lock said sear member and firing mem- 100 ber in firing position, means for guiding said slidable controller in its sliding movement, means for preventing shifting of said slid- 105 able controller, a spring actuated contacting member carried by said slidable controller and engaging said sear member, a grip- 110 safety member pivotally attached at one end thereof to said grip-stock and engageable at the other end thereof with said frame and 115 engageable with said slidable controller to block said slidable controller in upward position, and releasable from both said en- 120 gagements by grip-compression, a rod pivot- 125 ally attached at the upper end to said firing member, a spring seatably connected to said grip-safety member, movable means engag- 130 ing said grip-safety member for providing an abutment for the upper end of said spring and a seat for the lower end of said rod, a 135

- spring surrounding said stem and seated on said boss and abutting the under face of said shoulder to move the slidable controller upwardly to lock said sear member and firing hammer in firing position, a spring actuated contactor carried by said slidable controller for engaging said sear member, a grip-safety member pivotally attached at one end thereof to said grip-stock and provided with locking prongs for engaging said bottom-faces of the slidable controller, and engageable at the other end thereof with said frame to block said slidable controller in upward position, and releasable by grip-compression from both said engagements, a rod pivotally attached at the upper end to said firing hammer and provided with side-faces, a spring seatably connected to said grip-safety member, a cupped plunger engaging said grip-safety member and provided with an extending stem, said spring surrounding said stem, and said cupped plunger providing an abutment for the upper end of said spring and a seat for the lower end of said rod, a resisting and retracting member provided with arms for engaging said upper surfaces of the shoulder of the slidable controller and arms for engaging said side-faces of said rod, and a trigger member received in said slot of the slidable controller and provided with an end for engaging said lower end-face of the sear member. 10
11. In a firearm, in combination, a firing member movable to firing position and to fired position, sear means engageable with said firing member, slidable means, means for moving said slidable means in direction 90 for locking said sear means and firing member in firing position, spring means, means for connecting said firing member to said spring means for moving said firing member to fired position, and means engageable with said connecting means and engageable with said slidable means for resisting movement of said firing member from firing position to fired position, and for moving said slidable means in direction 100 reverse to the first mentioned direction when said firing member is moved to fired position. 15
12. In a firearm, in combination, a sliding breechaction, a frame of said firearm comprising a grip-stock, a firing hammer movable to firing position and to fired position, and provided with a cock-notch, a sear member provided with an upper end face for engaging said cock-notch and provided with a lower end-face, a slidable controller provided with an end-face for engaging said sliding breechaction, and provided with a slot for receiving a trigger member, and provided with bottom-faces, and provided with a shoulder having upper surfaces and an under face and an extending stem from said under face, guide-faces for the slidable controller at its upper end, a boss mounted on said grip-stock for providing a seat for said stem and for preventing shifting of said slidable controller at its lower end, a spring surrounding said stem and seated on said boss and abutting the under face of said shoulder to move the slidable controller upwardly to lock said sliding breech action, and lock said sear member and firing member in firing position, a spring actuated contactor carried by said slidable controller engaging said sear member, a grip-safety member pivotally attached at one end thereof to said grip-stock, and provided with locking-prongs for engaging said bottom-faces of the slidable controller and being engageable at the other end thereof with said frame to block said slidable controller in upward position, and releasable by grip-compression from both said engagements, a rod pivotally attached at the upper end to said firing hammer and provided with side-faces, a spring seatably connected to said grip-safety member, a cupped plunger engaging said grip-safety member and provided with an extending stem, said spring surrounding said stem, and said cupped plunger providing an abutment for the upper end of said spring and a seat for the lower end of said rod, a resisting and retracting member provided with arms for engaging said upper surfaces of the shoulder of the slidable controller and arms for engaging said side-faces of said rod, and a trigger member received in said slot of the slidable controller and provided with an end for engaging said lower end-face of the sear member. 20
13. In a firearm, in combination, a firing member movable to firing position and to fired position, sear means engageable with said firing member, slidable means, means for moving said slidable means upwardly for locking said sear means and firing member in firing position, spring means, means for connecting said firing member to said spring means for moving said firing member to fired position, and means engageable with said connecting means and engageable with said slidable means for resisting movement of said firing member from firing position to fired position, and for moving said slidable means in direction 110 reverse to the first mentioned direction when said firing member is moved to fired position. 25
14. In a firearm, in combination, a sliding breechaction, a firing member movable to firing position and to fired position, sear means engageable with said firing member, slidable means engageable with said sliding breechaction, means for moving said slidable means in direction for locking said 115 sliding breechaction, and locking said sear means and firing member in firing position, spring means, means for connecting said firing member to said spring means for moving said firing member to fired position, and means engageable with said connecting means and engageable with said slidable means for resisting movement of said firing member from firing position to fired position, and for moving said slidable means in direction 120 reverse to the first mentioned direction when said firing member is moved to fired position. 30
15. In a firearm, in combination, a firing member movable to firing position and to fired position, sear means engageable with said firing member, slidable means, means for moving said slidable means upwardly for locking said sear means and firing member in firing position, spring means, means

for connecting said firing member to said spring means for moving said firing member to fired position, and means engageable with said connecting means and engageable with said slidable means, for resisting movement of said firing member from firing position to fired position, and for moving said slidable means downwardly when said firing member is moved to fired position.

14. In a firearm, in combination a sliding breechaction, a firing member movable to firing position and to fired position, sear means engageable with said firing member, slidable means engageable with said sliding breechaction, means for moving said slid- 5
able means upwardly for locking said sliding breechaction, and locking said sear means and firing member in firing position, spring means, means for connecting said 10 firing member to said spring means for moving said firing member to fired position, and means engageable with said connecting means and engageable with said slidable means for resisting movement of said firing 15 member from firing position to fired position, and for moving said slidable means downwardly when said firing member is moved to fired position.

15. In a firearm, in combination, a firing member movable to firing position and to fired position, a sear member engageable with said firing member, a slid- 20
able controller, an actuator for moving said slidable controller in direction for locking said sear member and firing member in firing position, spring means, means for connecting said firing member to said spring means for moving said firing member to fired position, and means engageable with said connecting 25 means and engageable with said slidable controller for resisting movement of said firing member from firing position to fired position, and for moving said slidable controller in direction reverse to the first-men- 30
tioned direction when said firing member is moved to fired position.

16. In a firearm, in combination, a sliding breechaction, a firing member movable to firing position and to fired position, a sear member engageable with said firing member, a slid- 35
able controller engageable with said sliding breechaction, an actuator for moving said slidable controller in direction for 40
locking said sliding breechaction, and lock said sear member and firing member in firing position, a spring, a rod for connecting said firing member to said spring for moving said firing member to fired position, and means engageable with said rod and engageable with said slidable controller for resisting movement of said firing member from firing position to fired position, and for moving said slidable controller downwardly when 45
said firing member is moved to fired position.

locking said sliding breechaction, and lock- 55
ing said sear member and firing member in firing position, spring means, means for connecting said firing member to said spring means for moving said firing member to fired position, and means engageable with said connecting means and engageable with 60
said slidable controller, for resisting movement of said firing member from firing position to fired position, and for moving said slidable controller in direction reverse to the first mentioned direction when said fir- 65
ing member is moved to fired position.

17. In a firearm, in combination, a firing member movable to firing position and to fired position, a sear member engageable with said firing member, a slidable controller, an 70
actuator for moving said slidable controller upwardly for locking said sear member and firing member in firing position, a spring, a rod for connecting said firing member to said spring means for moving said firing 75
member to fired position, and means engage-
able with said rod and engageable with said
slidable controller for resisting movement of
said firing member from firing position to
fired position, and for moving said slidable 80
controller downwardly when said firing
member is moved to fired position.

18. In a firearm, in combination, a slid- 85
ing breechaction, a firing member movable to firing position and to fired position, a sear member engageable with said firing member, a slidable controller engageable with said sliding breechaction, an actuator for moving said slidable controller upwardly to lock 90
said sliding breechaction, and lock said sear member and firing member in firing position, a spring, a rod for connecting said firing member to said spring for moving said firing member to fired position, and means engageable with said rod and engageable with said slidable controller for resisting movement of said firing member from firing 95
position to fired position, and for moving said slidable controller downwardly when said firing member is moved to fired posi- 100
tion.

JOHN D. PEDERSEN.
